United States Patent Office

Des. 227,130
Patented June 5, 1973

227,130

CHILD'S RIDING VEHICLE

Francis E. Pavolko, Albion, and Donald V. Godfrey,
Fairview, Pa., assignors to Louis Marx & Co., Inc.,
New York, N.Y.

Filed May 3, 1972, Ser. No. 250,109

Term of patent 14 years

Int. Cl. D21—01

U.S. Cl. D34—15 AJ

T19.1.

T19.2.

FIG. 3.

FIG. 1 is a front perspective view of a child's riding vehicle showing our new design;

FIG. 2 is a rear perspective view thereof;

FIG. 3 is a side elevational view thereof; and

FIG. 4 is a bottom plan view thereof.

We claim:

The ornamental design for a child's riding vehicle, as shown.
